UNITED STATES PATENT OFFICE.

GEORGE E. BALDWIN, OF PLAINFIELD, NEW JERSEY, ASSIGNOR TO JOSEPH ROBINSON, OF WESTMOUNT, QUEBEC, CANADA.

TRAIN-PIPE CONNECTER.

Application filed April 9, 1921, Serial No. 459,881. Renewed November 6, 1925.

This invention relates to automatic train pipe connectors and particularly to means for supporting the coupling head.

It is the object of the invention to provide a support for the coupling head which will readily permit movement of the head in all directions, which is simple in construction, which has comparatively few parts and which can be easily manufactured and assembled. Another object is to provide an improved means for securing the coupling head in different positions relative to the coupler head of the car. Other objects and advantages of the improved construction will be apparent to those skilled in the art.

The invention is illustrated in the accompanying drawings forming part of this specification and in which:

Figure 1 is a longitudinal vertical sectional view partly in elevation showing the improved construction;

Figure 2 is a horizontal longitudinal section of the construction certain parts being omitted;

Figure 3 is a transverse vertical sectional view on the line 3—3 of Figure 1;

Figure 4 is a detailed view showing one of the filler blocks used for securing the bracket in different positions.

Referring to the drawings in detail 10 represents a lug to which the bracket 11 is secured, this lug being rigidly attached to the car coupler or any other fixed part of the car to which the device is applied. At 35 its upper end the bracket 11 is provided with spaced portions or ears 11^a which are adapted to lie upon opposite sides of the lug 10, this lug being provided with suitable holes through which fastening bolts 12 are inserted for securing the bracket to the lug.

Each of the ears 11^a of the bracket 11 is provided with an elongated opening in which a reversible filler block 13 is mounted, each of these filler blocks being provided with apertures 14 through which the bolts 12 heretofore mentioned are adapted to pass and which serve to secure the bracket 11 to the lug 10. The openings 14 of the filler blocks 13 are offset or unsymmetrically positioned with reference to the center of the blocks, that is, they are so arranged that when these blocks are reversed or turned end to end the bracket 11 will be secured in dif-

ferent positions. The filler blocks thus constitute means by which the bracket may be adjusted longitudinally of the car so that the position of the coupling head supported by the bracket may be varied with reference to the face of the car coupler.

Near its lower end the bracket 11 is shaped to form a cylindrical bearing portion or member 15 beneath which there is provided a head or enlarged portion 16 for a purpose hereinafter described. A pivot block 17 is arranged to engage the bearing portion 15 of the bracket, this block being provided intermediate its ends with a curved seat 18 which bears against the curved front portion of the cylindrical bearing member 15. The pivot block 17 is also provided with a trunnion 19 on each side of the seat 18 or on each side of the bearing portion 15 of the bracket.

A stem 20 extends rearwardly of the bracket 11, the front end of which is provided with spaced portions 20^a shaped to engage the trunnions 19 of the pivot block 17. The portions 20^a of the stem are preferably made in the shape of hooks which fit over the trunnions 19. At its rear end the stem 20 is threaded and upon such threaded portion an abutment 21 is adjustably mounted.

The coupling head 22 of my improved construction may be of the ordinary type provided with wings 22^a for cooperating with the wings of a mating head. To support the head in front of the bracket there is provided a supporting member 23 which is secured to the head in any suitable manner, preferably by being attached to the usual conduit 22^b which extends laterally from the rear portion of the head and which is adapted to receive a train pipe hose. The supporting member 23 is preferably formed of spaced arms 23^a which extend rearwardly from the head 22 to the rear of the bracket and to the rear portion of said arms 23^a there is secured a flange or projection 24 which is adapted to contact with the rear face of the bracket, such flange or projection 24 preferably being formed integral with said arms 23^a. The rear face of the flange or projection 24 is provided with a suitable seat 25 and a coiled spring 26 is arranged between said seat and the abutment 21 heretofore mentioned on the stem 20.

The spring 26 acts to hold the flange 24 of the supporting member 23 yieldingly against the rear face of the bracket so that the head 22 is maintained in proper position 5 to cooperate with the mating head on another car. The tension of the spring 26 may be varied by adjustment of the abutment 21 on the stem 20. By reason of the pivotal engagement between the stem 20 and the trunnions of the pivot block 17 and the pivotal engagement of the pivot block on the bearing portion 15 of the bracket it is apparent that the coupling head will be free to move in all directions to accommodate the relative 15 movement between cars in passing around curves or over uneven track. The arms 23^a of the supporting member 23 have their inner surfaces arranged in close proximity to the ends of the trunnions 19 so that rotation of the coupling head on its longitudinal axis is prevented and the pivot block 17 is prevented from downward movement by the head 16 on the lower end of the bracket.

Various changes may of course be made in 25 the details of the foregoing construction without departing from the scope of the invention which it should be understood is not limited to such specific details.

Having thus described the invention what 30 I claim as new and desire to secure by Letters Patent is:

1. In a train pipe connector, a bracket having a bearing portion adjacent its lower end, a pivot block having a seat intermediate 35 its ends engaging said bearing portion of the bracket, trunnions on said block at opposite sides of said seat, a stem having portions pivotally engaging said trunnions, an abutment on said stem, a coupling head, a member connected therewith and extending to the rear of said bracket and carrying a flange or projection adapted to contact with the rear of the bracket, and a coiled spring arranged 40 between said flange and said abutment.

45 2. In a train pipe connector, a bracket having a vertically arranged bearing portion adjacent its lower end, a horizontally arranged pivot block having a seat intermediate 50 its ends engaging said bearing portion of the bracket, trunnions on said block at opposite sides of said seat, a stem pivotally engaging said trunnions and extending rearwardly of said bracket, a coupling head, a supporting member therefor extending to 55 the rear of the bracket and having a flange or projection for contacting with the rear of the bracket, and a spring carried by said stem and bearing against said projection.

60 3. In a train pipe connector, a bracket having a substantially cylindrical bearing portion adjacent its lower end, a pivot block having a curved seat intermediate its ends 65 engaging said bearing portion of the bracket, said block having a trunnion on either side of said seat, a stem pivotally engaging said

trunnions, a coupling head, a member connected therewith and extending rearwardly past said bracket and having a flange or projection for contacting with the rear face of the bracket, and a spring supported by 70 said stem and acting to hold said projection against the bracket.

4. In a train pipe connector, a bracket having a bearing portion adjacent its lower end, a pivot block having a seat intermediate 75 its ends engaging said bearing portion, a stem having spaced portions spanning said bearing portion of the bracket and engaging said pivot block, a coupling head, a member connected thereto and extending 80 rearwardly and spanning said spaced portions of said stem, said member having a flange or projection adapted to contact with the rear face of the bracket, and a spring carried by said stem and acting against said 85 flange or projection to hold the same against the bracket.

5. In a train pipe connector, a bracket, a vertically arranged bearing member thereon, a horizontally arranged pivot block pivotally 90 supported intermediate its ends on said bearing member, a stem extending rearwardly of said bracket and having spaced portions pivotally engaging said block on opposite 95 sides of said bearing member, an abutment on said stem, a coupling head, a member secured thereto and extending rearwardly past said bracket and having a flange or projection for engaging the rear face of the bracket and a spring arranged between said 100 abutment and said flange.

6. In a train pipe connector, a bracket having a head adjacent its lower end and having a bearing portion above said head, a pivot block extending transversely of the 105 bracket and having a seat intermediate its ends engaging said bearing portion, a stem pivotally connected to said block on opposite sides of said seat, an abutment on said stem, a coupling head, a member connected thereto 110 and extending rearwardly and having spaced portions arranged on opposite sides of said bracket and also having a flange or projection for engaging the rear face of the bracket, and a spring on said stem between 115 said abutment and said flange.

7. In a train pipe connector, a bracket having a bearing surface, a pivot block arranged transversely of the bracket and having intermediate its ends a part pivotally 120 engaging said bearing surface, a stem having spaced portions engaging said block on opposite sides of said bracket, a coupling head, a member extending rearwardly therefrom and having a flange or projection for engaging 125 the rear face of the bracket and a coiled spring on said stem for holding said flange against the bracket.

8. In a train pipe connector, a bracket having a vertically arranged curved bearing 130

surface, a pivot block extending transversely of the bracket and having approximately midway of its ends a part pivotally engaging said bearing surface of the bracket, a coupling head, a member extending rearwardly therefrom and having a flange or projection for engaging the rear face of the bracket, and means for yieldingly holding said block against said bearing surface and said flange against the rear face of the bracket.

9. In a train pipe connector, a bracket having a vertically arranged bearing surface, a pivot block having a seat intermediate its ends engaging said bearing surface, a coupling head, a member extending rearwardly therefrom and having spaced arms arranged adjacent the ends of said pivot block, said member also having a flange or projection for engaging the rear face of the bracket, and a coiled spring for holding said block against said bearing surface and said flange against the bracket.

10. In a train pipe connector, a bracket, a coupling head, a supporting member therefor extending rearwardly and having a flange or projection adapted to contact with the rear face of the bracket, said bracket having a bearing member provided with a curved surface facing toward said head, a pivot block having a curved seat approximately midway of its ends pivotally engaging the curved surface of said bearing member, and means engaging said block and said flange for yieldingly holding the latter against the rear face of the bracket.

11. In a train pipe connector, a bracket, a lug to which said bracket is secured, one of said parts having an elongated opening, a reversible filler block mounted in said opening and having an aperture therein for receiving a bolt, the other part also having an aperture for receiving a bolt, said aperture in the block being offset from the center of said block, whereby the position of said bracket will be changed when said filler

block is reversed and the bracket secured to the lug.

12. In a train pipe connector, a bracket, a coupling head supported by the bracket, a perforated lug to which the bracket is secured, said bracket having a horizontally arranged elongated opening therein, a reversible filler block arranged in said opening and having an aperture for receiving a fastening bolt passing through said block and said lug, said aperture being offset from the center of said block whereby when said block is reversed in said opening the position of the bracket and head will be changed.

13. In a train pipe connector, a bracket, a lug, a reversible member carried by one of said parts, said member having bolt receiving openings unsymmetrically arranged with reference to the center thereof, whereby when said member is reversed the position of said openings will be changed, the other of said parts having bolt receiving openings adapted to register with the openings in said member when in either position, and bolts passing through said registering openings to secure said bracket to said lug in either position of said reversible member.

14. In a train pipe connector, a bracket having a vertically arranged curved bearing surface, a pivot block extending transversely of the bracket and having intermediate its ends a part pivotally engaging said bearing surface on the bracket, a coupling head, a member extending rearwardly therefrom and having spaced portions lying on opposite sides of said bracket and said pivot block, said member also having a flange or projection for engaging the rear face of the bracket, and means for yieldingly holding said block against said bearing surface and said flange against the rear face of the bracket.

In testimony whereof I affix my signature.
GEORGE E. BALDWIN.
